UNITED STATES PATENT OFFICE.

RHODA McGRAW, OF SYRACUSE, NEW YORK.

SUPPLY-VALVE FOR FLUSH-TANKS.

No. 846,132.

Specification of Letters Patent.

Patented March 5, 1907.

Application filed June 4, 1906. Serial No. 320,182.

To all whom it may concern:

Be it known that I, RHODA McGRAW, of Syracuse, in the county of Onondaga, in the State of New York, have invented new and useful Improvements in Supply-Valves for Flush-Tanks, of which the following, taken in connection with the accompanying drawings, is a full, clear, and exact description.

This invention relates to certain improvements in supply-valves for flush-tanks, in which the water-supply is controlled by a suitable float.

The essential object of this improvement is to cause the supply-valve to open and close quickly, so that the water-supply is instantly "full on" or "full off," thereby preventing the passage of the water in fine jets between the valve and its seat and obviating the consequent cutting or channeling of the valve and its seat and also avoiding the incidental singing noise which usually accompanies the gradual closing of the supply-valve.

The invention lies in inclosing the valved end of the supply-pipe in a chamber of comparatively large cross-sectional diameter having a diaphragm to which the main supply-valve and float is attached, and to provide such chamber with a lateral discharge-nozzle of less cross-sectional area than the main supply-passage and having a valve whereby the cross-sectional area of the passage may be restricted more or less for the purpose of producing a back pressure upon the diaphragm sufficient to hold the main valve open until overcome by the pressure of the water upon the float, whereupon the valve is instantly closed by the water-pressure in the tank acting upon said valve.

In the drawings, Figure 1 is a longitudinal sectional view of a flush-tank equipped with my improved supply-valve, which is shown in elevation. Fig. 2 is an enlarged sectional view of a portion of the tank, showing the supply-valve in section.

The flush-tank, as 1, is provided with a supply-pipe 2 and a flush-pipe 3, the supply-pipe terminating within the reservoir 1 and is provided with a main valve 4, controlling the water-supply, while the flush-pipe 3 also terminates within the reservoir and is provided with a valve 5, controlling the exit of water from the tank or reservoir 1.

The valve 4 is mounted on the lower end of a stem 6, having its upper end pivotally attached at 7 to one end of a float-arm 8, which is fulcrumed at 9 and has its free end pro-

vided with a float 10. The valve 4 and its seat, as 11, are inclosed within a suitable shell or water-chamber 12, having a flexible top or diaphragm 13 and a lateral extension 60 or discharge-nozzle 14 of somewhat less cross-sectional area than the supply-pipe 2, said nozzle being provided with pressure-regulator valve 15, whereby the size of the water-passage may be varied to create a back pressure upon the diaphragm sufficient to resist the uplift upon the float during the inflow of water to hold the valve 4 full open until the tank is practically filled.

The chamber 12 forms the inner terminus 70 of the water-inlet and is of greater cross-sectional area than that of the water-supply pipe, and the diaphragm 13, which is imperforate and impervious and forms the upper side of the chamber 12, is also of considerably 75 greater area than the cross-sectional area of the valved inlet. It therefore follows that if the valved outlet of the chamber 12 is restricted to less size than the inlet a back pressure or uplift will be exerted upon the 80 diaphragm 13 to lift the latter, and thereby hold the float down and valve 4 open, such back pressure being increased in proportion to the degree of reduction of the size of the outlet relatively to the inlet and also in proportion to the excess of area of the diaphragm over that of the inlet, and it is this 85 constricted discharge-passage, together with the magnified area of the diaphragm as related to the inlet, which forms the essential 90 feature of my invention—viz., to hold the inlet-valve open against the lifting pressure of the inflowing water acting on the float and tending to close the inlet-valve.

The inner or lower side of the diaphragm 95 13 is exposed to the inlet 2 and outlet 14, and its upper side is exposed to the interior of the main tank 1 through an opening 16 in a cap 17, which forms a convenient means for securing the diaphragm to the lower section 12 100 and also serves as a baffle-plate to prevent forcible discharge of the inflowing water through and above the tank in case the diaphragm 13 should be broken or punctured.

The discharge-passage 14 is always of less 105 cross-sectional area than the inlet-passage 2, and the area of the diaphragm 13 is always greater than the cross-sectional area of the inlet 2, the relative areas of said passages and diaphragm being proportioned according to 110 the water-pressure per unit of area in the supply-pipe 2, thereby establishing a back

pressure upon the diaphragm sufficient to resist the uplift of the water on the float during the filling of the tank to a predetermined level or until the uplift-pressure on the float 5 reaches a predetermined degree, which is regulated by the relative size of the outlet 14 or valve 15.

As soon as the uplift-pressure of the float reaches such predetermined degree the back 10 pressure upon the diaphragm is overcome and the accumulated uplift-pressure acting on the float instantly elevates said float and simultaneously closes the valve 4, the closing action of the valve 4 being accelerated by 15 reason of the fact that as soon as the valve begins to close the back pressure on the diaphragm and consequent resistance to the uplift of the float is at once reduced, allowing the water to lift the float with increased 20 speed, thus causing the instantaneous closing of the inlet-valve 4.

The entire mechanism involved in this invention is located within the main supply-tank, and the essential elements are the diaphragm of greater area than the inlet and the 25 restricted passage 14 of less area than that of the inlet, together with means, as the valve 15, for varying the size of the outlet and making it possible to use this invention with 30 any water-pressure.

What I claim is—

1. In combination with a flush-tank, a water-supply pipe, a water-chamber connecting with the water-supply pipe and provided 35 with a lateral discharge, an adjustable valve in the discharge, a diaphragm forming one side of the chamber, a main valve attached to the diaphragm and coacting with the inlet to regulate the flow of water into said chamber, and a float attached to the diaphragm.

2. In combination with a flush-tank having a valved water-inlet, a chamber inclosing

the inlet having one of its sides provided with a flexible diaphragm of greater area than the cross-sectional area of the inlet, said chamber 45 having a lateral discharge-passage of less cross-sectional area than the inlet, a valve for the inlet attached to the diaphragm, and a float also attached to said diaphragm.

3. A supply-valve for flush-tanks comprising a chamber having an inlet and an outlet of less cross-sectional area than the inlet, said chamber having a flexible impervious diaphragm at one side of the inlet and outlet and of greater area than the cross-sectional area 55 of the inlet, a valve for the inlet, and a float, both valve and float being attached to the diaphragm.

4. A water-supply valve for flush-tanks, comprising a water-chamber having an inlet 60 and an outlet, the latter being of less cross-sectional area than the inlet, a valve for the inlet, an additional valve in the outlet, a diaphragm forming one side of the chamber and attached to the inlet-valve, and having one 65 side exposed to the inlet and outlet, and its other side exposed to interior of the tank, and a float attached to the diaphragm.

5. In combination with the flush-tank a water-supply chamber in the tank having 70 an inlet and an outlet the latter being of less size than the inlet, a movable element forming one of the sides of the water-chamber, a valve for the inlet and a float, both valve and float being connected to said movable element, the latter being of greater area than 75 the inlet, and means for varying the size of the outlet.

In witness whereof I have hereunto set my hand this 29th day of May, 1906.

RHODA McGRAW.
